DESIGN FOR A FLY SWATTER

John L. Bennett, Decatur, Ill., assignor to U. S.
Manufacturing Corporation, Decatur, Ill.

Application May 16, 1934, Serial No. 51,801

Term of patent 14 years

To all whom it may concern:

Be it known that I, JOHN L. BENNETT, a citizen of the United States, and a resident of Decatur, county of Macon, and State of Illinois, have invented a new, original, and ornamental Design for a Fly Swatter, of which the following is a specification, reference being had to the accompanying drawing, forming part thereof.

In the drawing—

Figure 1 is a view in front elevation of a fly swatter embodying my design.

Figure 2 is a view in rear elevation of the same, parts of the handle being broken away.

I claim:

The ornamental design for a fly swatter as shown.
